UNITED STATES PATENT OFFICE.

HAROLD EDWARD SHERWIN HOLT, OF FARNBOROUGH, ENGLAND.

AERIAL ILLUMINATING DEVICE.

1,312,499.

Specification of Letters Patent.

Patented Aug. 5, 1919.

Application filed September 4, 1917. Serial No. 189,666.

To all whom it may concern:

Be it known that I, HAROLD EDWARD SHERWIN HOLT, hon. lieut. col., a subject of the King of Great Britain and Ireland, residing at The Grange, Farnborough, Hampshire, England, have invented certain new and useful Improvements in Aerial Illuminating Devices, of which the following is a specification.

10 This invention relates to aerial illuminating devices in which a flare or light-giving body of combustible material is attached to a parachute or parachute reflector which regulates the rate of descent of such body, 15 when caused to fall from a height and enable same to be used with effect by airmen on aeroplanes or airships to illuminate the ground below when landing in the dark or to illuminate a particular area for reconnoitering at night or for other purposes. Or 20 it may be fired from a catapult or by compressed air or other means from a tube or gun.

My present invention provides a construction of illuminating device of the type referred to wherein the parachute is held in a folded up condition in a casing which forms a permanent part of the flare or light giving body and the automatic release and opening 30 of the parachute, as well as the ignition of the flare are effected in a simple and practical manner with the object of enabling the illuminating device to be employed on any type of aircraft or projected from the 35 ground.

As the parachute casing forms a permanent part of the flare it remains on the flare after the parachute is expelled and in this respect my invention is broadly distinguished 40 from floating signal rockets and the like in which both the combustible material and the parachute are ejected at the same time from the casing of the rocket.

In a practical form of the invention the 45 flare consists of a cylindrical case containing combustible light-giving material and also forming a housing for the folded parachute which is connected by a flexible connection or by a spring with a wooden disk or piston 50 which is in turn connected with the flare by a short length of wire or the like. A small explosive charge of powder is placed in a recess in a wooden block on the end of the flare behind the disk or piston and a thin

celluloid or other covering which may be 55 suitably impregnated so as to readily burn away is arranged to cover ventilating holes in the block. When the flare is ignited the powder charge referred to is also ignited by a suitable fuse or quick match led along the 60 flare and blows the piston and parachute connected thereto out of the tube. When it is desired to drop the flare from a great height the parachute may be held partly reefed for a portion of the descent, means being provided for releasing the reefing cord automatically after a predetermined interval.

It will be evident that the illuminating devices described can be dropped out of aeroplanes and similar aircraft by hand after 70 being ignited and require no discharge tube but preferably a discharge tube is employed, electric contact strips being provided near the lower end of the tube in the path of suitable contacts on the flare body, the said contacts being adapted to convey an igniting current to the fuse of the flare from a suitable battery fixed on the discharging tube.

When a launching tube is used on airships, it is suspended some distance below the car 80 or platform and the flare is held in the tube by a suitable catch controlled by Bowden mechanism or the like to avoid accidental ignition of any explosive gases on the airship by sparking at the contacts of the 85 launching tube.

In the accompanying drawings:

Figure 1 is a central longitudinal section of an aerial illuminating device constructed according to this invention,

90

Fig. 2 is a transverse section through a discharge tube for the illuminating device illustrating the arrangement of electric contacts for conveying the igniting current to the flare and the means for guiding the flare in 95 the tube.

Fig. 3 is a diagram showing the flare with its supporting parachute in the open position.

Fig. 4 is a plan of the parachute fabric 100 illustrating a method of reefing same,

Fig. 5 illustrates in the side elevation a parachute rendered partly ineffective by reefing,

105

Fig. 6 is a detail view,

Fig. 7 is a sectional elevation of a parachute showing another method of reefing,

Fig. 8 is a view partly in section illustrat-

ing means for holding the reefing cord of the parachute and,

Figs. 9 and 10 are detail views illustrating in section and elevation the arrangement of contacts on the flare body.

As shown the flare comprises an outer tube or case *a* made of paper, wood or other light material capable of burning away with the flare material and closed at its lower end 10 by a wooden cap *b* which is arranged to fall off when the flare is ignited. A wooden partition or circular block *c* divides the case *a* into upper and lower compartments the lower compartment serving to hold the combustible flare material *d* and being closed by a cardboard disk *d'*, while the upper compartment forms a housing for the folded parachute *e*, and is closed by a wooden disk *f*. Extending from the partition or block 20 *c* in which it is fixed and passing centrally downward through the flare material *d* is a paper tube *g* which forms a passage for air through the center of the flare material and also for the electric igniting wires *h* and 25 quick match *i* but is temporarily closed at the lower end by a plug or cork *g'*. The igniting wires *h* are connected with tin foil contact strips *h'* on the outside of the case *a* such connection being shown conventionally 30 in Fig. 1 but preferably being made, as illustrated in Figs. 9 and 10, by first soldering the wires to metal plates *h''* fixed in recesses on the curved outer face of the block *c*, and pressing the lower ends of the tin foil contact strips *h'* through holes *h''* in the case *a*, so that they lie against the said metal plates 35 on the block *c* to which they are fixed by screws *h''* and washers.

From the contacts as described the wires 40 *h* pass through radially bored apertures *c'* and a centrally bored aperture *c''* in the block *c* into and along the tube *g* to the igniting cap of a time fuse *j* connected with the lower end of the flare and also by the 45 quick match *i* with a small explosive charge *l* contained in a central recess in the upper surface of the block *c*. Over the outer portion of the upper surface of the block a thin sheet *m* of celluloid is placed which preferably rests on annular ribs formed by 50 grooving the upper surface of the block *c* to enable the celluloid to readily burn away to uncover vent apertures *n* formed in the block thus affording a free passage for air through 55 the block when the celluloid is consumed. Above the block *c* a wooden piston *o* is placed to which the parachute *e* is attached, the piston being connected with the block *c* by a suspending wire *o'* of sufficient length 60 to allow the piston to move a short distance out of the tube when acted upon by the explosive charge *l* as hereinafter described.

As shown in Fig. 2 the flare tube or case *a* is guided in a discharge or launching tube *p* 65 by a longitudinally extending external guide

rib *a'* which slides in a groove in the tube *p* and insures the tin foil contact strips *h'* being moved over spring contact strips *p'* in the launching tube *p* to close the igniting circuit as the flare is being launched. Current is supplied to the said circuit by a battery which may be carried on the launching tube.

Instead of arranging a single external guide rib *a'* on the flare tube or case *a*, it 75 may have two ribs, preferably diametrically opposed and carrying the tin foil contact strips in which case the spring strips for making contact therewith would be mounted in guide grooves formed to guide the ribs 80 in the launching tube.

When the flare is intended to be launched at high altitudes the retardation of the descent by the parachute may be arranged to only become fully effective at a much lower 85 altitude in order that the descent of the flare may not be too long delayed. For this purpose a reefing cord *r* is laced through the fabric of the parachute as shown in Fig. 4 in such manner as to draw the same together 90 when pulled tight so that the parachute can only partly open as in Fig. 5 as long as the cord is held taut. For holding the cord it may be connected with the cap *b* by a wire 95 *r'* as in Fig. 3, said wire being in two parts joined at *r''*, by a solder which is capable of being melted by the heat of the flare to release the cord. In this connection a long delay fuse would be employed for timing the ignition of the flare. Instead of drawing the 100 parachute together by a single cord *r* laced through the fabric in the manner described, an inner set of cords *e''* similar to the suspending cords *e'* could be attached to the 105 fabric as shown in Fig. 7 at points in a circle nearer the center of the fabric than the cords *e'* and so held down as to prevent the full opening of the parachute until the cords 110 were released. These cords could be controlled by the wire *r'* in the manner described. The wire *r'* may be conveniently passed through the cap *b* to the parachute reefing cord or cords *e''* from a tube *s* arranged in the flare material *d*, as shown in Fig. 8.

In operation when the flare with its parachute is released or launched by discharging through the launching tube, an electric circuit is completed through the contacts *p'* *h'* and wires *h* which ignites the delay fuse *j* 115 then in turn ignites first the explosive charge *l* and after a further interval the flare *d*. When the powder *l* is exploded it drives the piston *o* with the parachute and disk *f* out of the case *a* and ignites the celluloid sheet 120 *m*. The flare then descends steadily under the control of the parachute and when ignited burns from the bottom end upward, the cap *b* falling away as soon as the flare 125 begins to burn.

What he claims and desires to secure by Letters Patent is:—

1. In combination with a launching tube, an aerial illuminating device comprising a flare or light giving body, a casing forming part of said flare or body, a parachute fastened to said flare and retained in folded condition in said casing, and means rendered operative by said tube for subsequently expelling the parachute and igniting the flare. 50
2. In combination with a launching tube, an aerial illuminating device comprising a casing, a partition dividing said casing into an upper and lower compartment, a flare or light giving body in the lower compartment, a parachute fastened to said flare and maintained in folded condition in the upper compartment, and means rendered operative by said tube for subsequently expelling 55 the parachute and igniting the flare. 60
3. In combination with a launching tube, an aerial illuminating device comprising a flare or light giving body, a casing forming part of said flare or body, a parachute fastened to said flare and retained in folded condition in said casing, means rendered operative by said tube for subsequently expelling the parachute, and means associated 65 with said first named means for igniting the flare. 70
4. In combination with a launching tube, an aerial illuminating device comprising a flare or light giving body, a casing forming part of said flare or body, a parachute fastened to said flare and retained in folded condition in said casing, and time fuses rendered operative by said tube and adapted to effect the expulsion of the parachute and ignition of the flare at different times. 75
5. In combination with a launching tube, an aerial illuminating device comprising a flare or light giving body, a casing forming part of said flare or body, said flare being provided with a central passage, a parachute fastened to said flare and retained in folded condition in said casing, and means 80

extended through said passage and rendered operative by the discharge of the device for expelling the parachute, and means associated with said first named means for igniting 50 the flare.

6. The combination with a launching tube of an aerial illuminating device comprising a flare or light giving body, a casing forming part of said flare or body, a parachute 55 fastened to said flare and retained in folded condition in said casing, a piston arranged underneath said parachute, and an explosive adapted to expel the piston and therewith the parachute, and means rendered 60 operative by said tube for igniting the explosive and the flare.

7. The combination with a launching tube provided with contacts adapted to be connected to a source of electrical energy, of 65 an aerial illuminating device, comprising a flare, a casing forming part of said flare, a parachute fastened to said flare and retained in folded condition in said casing, contacts secured to the casing and adapted to close 70 the circuit upon engaging the contacts of said tube, means in the circuit for igniting the flare, and means associated with said first named means for expelling the 75 parachute.

8. In combination with a launching tube provided with contacts adapted to be connected to a source of electrical supply, of an aerial illuminating device, comprising a flare or light giving body, a casing forming 80 part of said flare or body, and provided with contacts formed of tin foil strips and adapted to engage the contacts of said tube, a parachute fastened to said flare and retained in folded condition in said casing, means 85 rendered operative by the engagement of the contacts for expelling the parachute, and means for igniting the flare.

In testimony whereof he has affixed his signature.

HAROLD EDWARD SHERWIN HOLT.
